UNITED STATES PATENT OFFICE.

JOHN R. WENGLER, OF ALLENTON, MISSOURI.

DESIGN FOR A PIPE.

SPECIFICATION forming part of Design No. 29,363, dated September 20, 1898.

Application filed August 17, 1898. Serial No. 688,812. Term of patent 7 years.

To all whom it may concern:

Be it known that I, JOHN R. WENGLER, a citizen of the United States, residing at Al-
lenton, in the county of St. Louis and State
5 of Missouri, have invented and produced a
new and original Design for Pipes, of which
the following is a specification, reference be-
ing had to the accompanying drawings, forming
a part thereof.

10 Figure 1 is a perspective view of a pipe,
showing my design. Fig. 2 is a vertical sec-
tion of a pipe constructed in accordance with
my design.

15 As shown in the drawings, the leading or
material feature of my design consists in the
shape of the bowl of the pipe and the orna-
mentation thereof.

20 The body *a* of the bowl is substantially cy-
lindrical in shape and has at its upper edge
a projecting ring *b*, hemispherical in cross-
section, the said body tapering slightly to-
ward the bottom. At a point about one-third

of the way from the bottom of the bowl the
body is suddenly contracted, from which
point it is semi-ellipsoidal in form. Upon 25
the surface of the upper cylindrical portion
of the body is shown a shield of the United
States, consisting of the striped lower por-
tion with a field at the top having stars rep-
resented thereon. Centrally of the shield is 30
a curvilinear inclosure, within which is shown
a portrait.

The stem *c* of the pipe is shown as protrud-
ing from the bowl below the shield or me-
dallion.

35 Having thus described my invention, what
I claim, and desire to secure by Letters Pat-
ent, is—

The design for a pipe, substantially as
herein shown and described.

JOHN R. WENGLER.
